UNITED STATES PATENT OFFICE.

VLADIMIR KLODNYCKYJ, OF CHICAGO, ILLINOIS.

SWIMMING DEVICE.

Application filed August 22, 1927. Serial No. 214,511.

The present invention relates to swimming devices and has for its main object the provision of a device comprising one or more inflatable tubes which are attachable to straps which are adapted to engage the body of the wearer, in such a way that the device would not interfere with the movement of the swimmer's limbs.

Another object of the present invention is the provision of a device of the character indicated which has detachable parts so that in case of damage of some of the parts new parts may be substituted without impairing the utility of the entire device.

Another object of the present invention is the provision of means for attaching the inflatable tubes to the straps or belts by which the device is attached to the body of the user.

With the above general objects in view and others that will appear as the nature of the invention is better understood, the same consists of the novel construction, combination and arrangement of parts herein after more fully described, illustrated in the accompanying drawing and pointed out in the appended claims.

In the drawing forming a part of this application and in which like designating characters refer to corresponding parts throughout the several views,

Fig. 1 is a top elevational view of the device with parts spread out preparatory to affixing the same to the body of the user;

Fig. 2 is a side elevational view of the device, illustrating the position thereof while the same is affixed to the body of the user;

Fig. 3 is an enlarged sectional view of one of the inflatable tubes, the view being taken on line 3—3 of Fig. 1;

Fig. 4 is a cross-sectional view through the end of the inflatable tube showing the manner in which the same is affixed to one of the straps or belts, the view being taken on line 4—4 of Fig. 1; and

Fig. 5 is a side elevational view of one shoulder strap, the view being taken substantially on line 5—5 of Fig. 1.

Referring in detail to the present invention the same embodies three tubes 10, each of which has sealed ends 11, shown on Fig. 4, which fit within the respective straps or belts hereinafter described. The bottom of each of said tubes 10 is made thicker, as at 12 so as to prevent curving thereof under the pressure of the air when the tube is in-

flated, for the purpose that the same may closely fit the back of the user when the device is affixed to the body of a person. The remaining portion of each tube is thinner than the base 12, permitting curving thereof when the tube is inflated, as indicated by 13 on Fig. 3. Each tube, at its lower end, at its outer portion 13 is provided with valve stem 14 within which a suitable valve is positioned through which the air is supplied to the tube for the purpose of inflating the same.

The invention further embodies waist belt 15 which is adapted to fit the waist of the user, said waist belt having at one of its ends suitable buckle 16 for receiving the other end of the belt, by means of which buckle said waist belt is adjusted upon the waist of a person. Substantially at the central portion of said waist belt 15 there are three pockets 17 made in said belt 15 for the purpose of receiving therewithin the lower ends of tubes 10. Said pockets 17 correspond in shape to the ends of said tubes 10 so that said ends may snugly fit therewithin. Said waist belt 15 is preferably made of waterproof canvas, although other material may be used.

The means for attaching the lower ends of said tubes 10 to said waist belt 15 and within pockets 17 consist of a button which includes pin 18 embedded within the end of tube 10, and whose one end is flattened as at 19. The other end of said pin extends farther beyond the body of the tube and terminates in head 20 over which the outer portion of pocket 17 is passed and held upon pin 18, which arrangement prevents slipping of waist belt 15 from tubes 10. Two buttons 20 for each tube may be used, as shown on Fig. 1. It is understood that the outer sides of pockets 17 may be provided with button holes for passing heads 20 therethrough, so that the pin 18 will remain within the button hole. Thus the inner face of head 20 abutting the outer face of the outer side of pocket 17 will hold said outer side of said pocket firmly in engagement with the flattened end of tube 10. Since the pocket corresponds in size to the dimensions of the end of the tube remaining within said pocket said flattened end of the tube will snugly fit within the pocket. By virtue of this arrangement no fastening means for the flattened end of the tube at the inner side of the pocket is required.

For receiving the upper ends of tubes 10, which upper ends are of identical construction with the construction of the lower ends of said tubes, upper strip 21 is provided, 5 which rests upon the shoulder blades of the user when the invention is in an operative position upon the body of the user. Said upper strip is likewise provided with three 10 pockets 22 for receiving therewithin the upper ends of tubes 10. Said upper ends likewise have attaching buttons 23 having the construction in all respects corresponding to the construction of buttons 20, including a pin corresponding to pin 18 and flattened 15 head corresponding to head 19. Attached to buttons 23 at the outermost tubes 10 are shoulder straps 24. The lower ends of said shoulder straps 24 terminate in buckles 25 through which the body portion of the 20 straps pass for the purpose of adjusting the length of said straps 24, depending upon the size of the user. This arrangement will effect loops 26 shown on Figs. 2 and 5, and through which the waist belt 15 is adapted 25 to pass in the operative position of the device illustrated on Fig. 2. It will be seen that by shortening straps 24 by moving buckles 25 toward the shoulders of the user the shoulder straps 24 as well as inflatable 30 tubes 10 will snugly fit the body of the user.

Waist belt 15 may be attached to the trunks used for swimming, in which case said belt will support the trunks upon the 35 waist of the user as well as the device herein described.

One of the advantages in my invention resides in the fact that each of tubes 10 constitutes an independent unit so that if one tube is damaged or punctured the other 40 will have sufficient capacity to sustain the body in the water. Another advantage of the invention resides in the manner of attaching the ends of tubes 10 to the waist belt 15 and upper strip 21.

While there is described herein a preferred embodiment of the present invention, it is nevertheless to be understood that minor changes may be made therein without departing from the spirit and scope of the invention as claimed.

What I claim as new is:

1. A device of the character described

comprising a plurality of inflatable units, a waist belt, an upper strip, shoulder straps, said waist belt and said upper strip being 55 provided with a plurality of pockets for receiving and entirely closing the respective ends of said inflatable units, and means for attaching the ends of said inflatable units to said pockets.

2. A device of the character described comprising a plurality of inflatable units, a waist belt, an upper strip, shoulder straps, pockets provided in said waist belt and said upper strip for receiving and entirely closing the ends of said inflatable units, pins embedded in the ends of said inflatable units, and heads upon said pins, said pins being adapted to engage portions of said pockets remaining between the ends of said inflatable units and the said heads.

3. A device of the character described comprising a plurality of inflatable tubes, the ends of said tubes being sealed and being of a flat formation, portions of said tubes 75 being of thicker formation in cross-section than the remaining portions of said tubes, said thicker portions of said tubes normally fitting the body of a user, a waist belt at the lower ends of said tubes, pockets in said 80 waist belt for receiving the lower ends of said tubes, means for attaching said ends to said pockets, a strip at the upper ends of said tubes, pockets in said strip, means for attaching said upper ends of said tubes to said pockets, and shoulder straps connected to said strip, said waist belt being adapted to fit over the waist of a user and said shoulder straps being adapted to pass over the shoulders of a user and connect with said 90 waist belt.

4. A device of the character described comprising a plurality of inflatable units, a waist belt, an upper strip, shoulder straps, pockets in said waist belt and said upper strip 95 wherein the ends of said inflatable units may snugly fit, said pockets being adapted to entirely enclose said ends of said inflatable units, and means for fastening the ends of said inflatable units to said 100 pockets.

In testimony whereof I affix my signature.

VLADIMIR KLODNYCKYJ.
